UNITED STATES PATENT OFFICE.

GEORGE H. WHITTINGHAM, OF NEW YORK, N. Y., ASSIGNOR TO AUTOMATIC SWITCH COMPANY, A CORPORATION OF MARYLAND.

AUTOMATIC MOTOR-REVERSER.

No. 821,009.

Specification of Letters Patent.

Patented May 22, 1906.

Application filed December 9, 1902. Renewed October 21, 1905. Serial No. 283,804.

To all whom it may concern:

Be it known that I, GEORGE H. WHITTINGHAM, a citizen of the United States, residing at New York, in the county of New York and State of New York, have invented certain new and useful Improvements in Automatic Motor-Reversers, of which the following is a full, clear, and exact specification.

This invention relates to automatic motor-reversing apparatus; and its object is to provide an apparatus of this character wherein when the motor is reversed it is absolutely protected against the introduction of current until after it has first been stopped and is in condition to safely receive current to drive it in the opposite direction. Heretofore it has been attempted to accomplish this by mechanically latching the controlling-arm at determined times; but such devices have been to some extent within the control of the operator.

So far as I am aware I am the first to provide means for accomplishing the foregoing objects automatically independently of the operator and by means wholly beyond his control.

The invention comprises various features of advantage, which will be described more in detail hereinafter.

Referring more particularly to the drawings, Figure 1 is a diagram of an apparatus embodying my invention, illustrating the connections while the motor is running in one direction. Fig. 2 illustrates the connections immediately after the controlling-arm is moved to the reverse position, and Fig. 3 illustrates the connection while the motor is running in the opposite direction.

A represents the armature of the motor, and B the field.

C represents an automatic motor-starter of any convenient type adapted to automatically cut out resistance from the armature-circuit when said circuit is made and to insert said resistance when the circuit is broken.

1 and 2 represent the terminals of the circuit from which the motor is to be driven. The field-circuit of the motor is through the blade 3 to the contact 4 and wire 5 to field B, thence through wire 6 to and through coil 7 and wires 8 and 9 to terminal 2. The armature-circuit when the motor is running in the direction of Fig. 1 is from wire 5 through

wire 10 to blade 11 and contact 12 and 55 through wires 13 and 14 to the automatic starter C, thence wire 15 to armature A, and thence by wires 16 and 17 to contact 18 and blade 19 and wires 20 and 9 to terminal 2. When the blades 11 and 19 are moved into 60 engagement with the opposite contacts 21 and 22, a circuit is established through the armature in the opposite direction, as follows: terminal 1, blade 3, contact 4, wires 5 and 10, blade 11, contact 21, wires 23 and 16, 65 armature A, wire 15, automatic starter C, wires 14 and 24, contact 22, blade 19, wires 20 and 9 to terminal 2.

The blades 11 and 19 of the reversing-switch D are mounted upon a common support 25, adapted to be moved to bring the blades 11 and 19 into contact with contacts 12 and 18, respectively, or with contacts 21 and 22, respectively. The movement of the support is controlled in this instance by oppositely-acting solenoids, the cores of which, 70 26 and 27, are attached to the respective sides of the support 25. The coils 28 and 29 of the solenoids are arranged to act in opposite directions and connected across the 75 line in series with each other. The circuit is as follows: terminal 1, wire 30, coils 28 and 29, wire 31, wire 9 to terminal 2. The cores 26 and 27 are so adjusted that when one core is drawn into its surrounding coil 80 the other pole will be more or less withdrawn from the influence of its coil. Therefore when coils 28 and 29 are energized the blades 11 and 19 are moved to make contact with the contacts on one side they will be held 85 there owing to the coil on that side having the greater influence upon its core.

The blades 32 and 33 of the operating-controller E are adapted, respectively, to connect the contacts 34 and 35 or 36 and 37 and 90 38 and 39 or 40 and 41. A wire 42 leads to the coil 43, and coil 43 is connected by wire 44 with contacts 35 and 36. Coil 43 controls the core 45, which is connected to blade 3, thus closing blade 3 upon contact 4 when 95 coil 43 is energized. The contacts 34 and 37 are respectively connected by the wires 46 and 47 with the contacts 48 and 49, one of which blades is engaged by the blade 19, according to whether the blade is at one side or 100 the other. A circuit through the coil 43 will therefore be provided in either position of the support 25 and its blades. When in the

- position shown in Fig. 1, the circuit is as follows: terminal 1, wire 42, coil 43, wire 44, contact 36, blade 32, contact 37, wire 47, contact 49, blade 19, wires 20 and 9 to terminal 2.
- 5 When the controller E and support and contact-blades are moved into the position shown in Fig. 3, the circuit is as follows: terminal 1, wire 42, coil 43, wire 44, contact 35, blade 32, contact 34, wire 46, contact 48, 70 blade 19, wires 20 and 9 to terminal 1.
- 10 The support 25, carrying the contact-blades 11 and 19, is moved by short-circuiting one of the coils 28 or 29 and permitting the other coil to move the blades. When 15 blade 33 of the controller E connects contacts 38 and 39, coil 29 is short-circuited, thus: from wire 50 to contact 38, blade 33 to contact 39, wire 51 to contact 52, contact-bar 53, contact 54, wire 55 to coil 29 and wire 31.
- 20 When blade 33 connects contacts 40 and 41, coil 28 is short-circuited, thus: wire 55, contact 54, blade 53, contact 52, wire 51, contact 40, blade 33, contact 41, wire 56, wire 30, coil 28.
- 25 Contact-bar 53 is carried by the core 57, which is surrounded by coil 7, and therefore as long as coil 7 is energized blade 53 will be held out of engagement with its contacts, and thus neither of the above short circuits 30 can be established while current is passing through coil 7.
- 35 The operation is as follows: The circuit through coil 43 being closed, the coil holds blade 3 against contact 4, and thus closes the circuits through the field and through the motor, as before described; but as long as current is passing through the field of the motor, which is in series with coil 7, coil 7 will hold blade 53 away from contacts 52 and 54 and 40 neither of the coils 28 or 29 can be short-circuited, no matter what the position of controller E. Coil 28 will therefore continue to hold the blades 11 and 19 in engagement with their contacts. When controller E is moved 45 to the opposite position, as shown in Fig. 2, its first effect is to break the circuit through magnet 43, and thus release blade 3, whereupon the main circuit through the field and through the armature is broken, as illustrated in Fig. 2. As the field-coil B is connected in shunt to the armature whether the reversing-switch is in one position or the other, then when the main circuit is opened at 4 the armature continuing to rotate will 55 supply current to the field-circuit which includes coil 7. Thus bar 53 will be held away from contacts 52 54. Therefore as long as this condition continues the coil 29 cannot be short-circuited and the reversing-switch D 60 must remain in its original position. This condition of the circuits continues as long as there is any current of appreciable strength in the armature and field circuit. When the current dies out of the field-winding, due to 65 the armature coming to rest, the coil 7 will be

deenergized and core 57 will drop, causing blade 53 to connect contacts 52 and 54, whereupon coil 28 is short-circuited, as before described. Thereupon coil 29, which receives double current when the other coil is short-circuited, becomes operative to move the support 25, carrying blades 11 and 19, so that blades 11 and 19 contact, respectively, with contacts 21 and 48 and 22, as shown in Fig. 3. When blade 19 contacts with contact 48, the circuit through coil 43 is again established and coil 43 again closes the motor-circuit through the field and armature through blade 3. Thereupon the motor is started through the automatic starter C; but the current entering the armature in the opposite direction causes the motor to operate accordingly. It will be noted that at the time the current is first introduced to the motor in the opposite direction there is no current in the motor, and the throwing of the reversing-switch will therefore not be attended by objectionable sparking. As soon as the field is energized coil 7 again breaks the circuit through contacts 52 and 54 and 90 prevents either of the coils 28 and 29 from being short-circuited.

In order to insure that when the armature-circuit of the motor is opened a short circuit through the motor-armature and a braking 95 resistance shall be established and the connection thereof maintained while necessary and at the same time shall prevent the main armature-circuit from being reestablished until the current in short circuit is below a 100 determined value, I provide the extension 58 upon blade 3, the extension carrying the contact-bar 59, insulated from the blade, but adapted to connect contacts 60 61 when blade 3 is out of contact with contact 4. 105 Contact 60 is connected with one terminal of armature A by wire 62, which includes the braking resistance 63, and contact 61 is connected with the other terminal of the armature by wire 64, which includes coil 66. Coil 110 66 surrounds core 65, which is attached to extension 58, and thus when coil 66 is energized it holds the bar 59 in engagement with contacts 60 and 61. Whenever magnet 43 releases blade 3 and the spring draws it back 115 and closes the circuit through bar 59, the short circuit through the motor-armature and braking resistance is established, and the reactance-current in this circuit energizes coil 66, and thus not only prevents the bar 59 120 from chattering against its contacts, but also prevents the circuit from being broken as long as the reactance-current is so large as to cause sparking upon the breaking of its circuit. As soon as the reactance-current dies 125 out the coil 66 becomes powerless and permits blade 3 to be moved. The strength of coil 66 will of course be adjusted according to individual conditions.

It will be noted that in the apparatus 130

above described it is wholly beyond the power of the operator to operate the motor in any other manner than that determined upon. Current cannot be introduced to the motor 5 to start it in the opposite direction until the field is entirely free of current, which condition can only exist when the motor has come to a complete stop. Furthermore, the switch will remain in the position set to run 10 the motor in one direction and will not break the circuit except where a reversal of the motor is intentional. Thus the motor may be restarted again in the same direction without disturbing the connections of the reversing- 15 switch.

It will be understood, of course, that the construction above described may be modified in various respects without departing from the invention, and I therefore desire it 20 to be understood that I do not limit myself herein to the specific construction herein shown.

Obviously the connections may be arranged so that the current in the field-circuit 25 is reversed instead of that in the armature-circuit.

Having thus described my invention, I declare that what I claim as new, and desire to secure by Letters Patent, is—

30 1. The combination with the armature and field windings of a motor, of means for preventing a reversal of current in one of said windings except when the current in the other winding is less than a determined value.

35 2. The combination with a motor, of means for reversing the current in the armature-winding, and means controlled by the strength of current in the field-winding for preventing such reversal except when the current in the 40 field-winding is less than a determined value.

45 3. The combination of a motor and a reversing-switch, means for setting the same, and means for maintaining the same in set position except when the current in the armature-winding is less than a determined value.

50 4. The combination with a motor, and a reversing-switch, oppositely-acting coils for operating the same, means for short-circuiting either of said coils, and means for preventing such short-circuiting except when the current in one of the motor-windings is below a determined value.

55 5. The combination with a motor, of a reversing-switch, oppositely-acting coils for operating the same, means for short-circuiting either of said coils when the current in one of the motor-windings is below a determined value, and means whereby upon making said short circuit current is introduced to 60 the motor.

65 6. The combination with a motor, of a reversing-switch, and oppositely-acting electromagnets for operating the same, said electromagnets being adapted to normally hold said switch in either one of its running posi-

tions, and means for preventing the switch from operating until the speed of the motor falls below a determined rate.

7. The combination with a motor, of a reversing-switch, two oppositely-acting forces 70 for moving the switch to either one of two positions, and means whereby said forces normally hold said switch in either of said positions when moved thereto, and means for preventing the switch from operating until 75 the speed of the motor falls below a determined rate.

8. The combination with a motor, of a reversing-switch, armatures connected to the opposite sides of said switch, and two oppositely-acting coils respectively surrounding said armatures, said coils and armatures being so disposed that when the switch is moved to one side the equilibrium of the coils will be 80 unbalanced.

85 9. The combination with a motor, of a reversing-switch, and two oppositely-acting electromagnets for operating said switch, the equilibrium of said electromagnets being unstable, and means for changing said equilibrium when the speed of the motor falls below 90 a determined rate.

10. The combination with a motor, of a reversing-switch, two oppositely-acting electromagnets for operating said switch, the 95 equilibrium of said electromagnets being unstable, and means for changing said equilibrium when the current in one of the motor-windings is less than a determined value.

100 11. The combination with a motor, of a reversing-switch, two oppositely-acting electromagnets for operating said switch, the equilibrium of said electromagnets being unstable, and means for preventing a change of 105 equilibrium except when the current in one of the motor-windings is less than a determined value.

11. The combination with a motor, of a field and armature windings therefor, a reversing-switch in the armature-circuit, and means for preventing the throwing of the reversing-switch except when the current in the field-winding is less than a determined value, substantially as described.

115 12. The combination with a motor, of field and armature windings therefor, a reversing-switch in the armature-circuit, a controller adapted to establish circuits which shall become operative upon the throwing of the reversing-switch, and means whereby 120 after said controller is operated the reversing-switch will be automatically thrown when the current in one of the motor-windings is less than a determined value, substantially as described.

125 13. The combination with a motor, of field and armature windings therefor, a reversing-switch in the armature-circuit, a circuit-closing switch adapted to establish the field and armature circuits upon the operation of the reversing-switch,

130

means for establishing a short circuit through the armature-circuit and a braking resistance when said circuit-closing switch is opened, and means for maintaining said short circuit until the current therein is less than a determined value.

15 15. The combination with a motor of a circuit-closing switch therefor, means for establishing a short circuit through the motor-armature and a braking resistance upon the opening of said circuit-closer, and means for maintaining said circuit as long as the current therein is above a determined value, substantially as described.

15 16. The combination with a motor, of a reversing-switch, a controlling-switch for opening the main circuit and for operating the re-

versing-switch and automatic means for preventing the operation of the reversing-switch until the speed of the motor has fallen below a determined rate.

17. The combination with a motor, of a reversing-switch, and automatic means for controlling the latter, said means being allowed to operate the reversing-switch only when the speed of the motor has fallen below a determined rate.

In testimony whereof I affix my signature in presence of two witnesses.

GEORGE H. WHITTINGHAM.
